JOHN W. CURRAN, OF NEWPORT, KENTUCKY.

WASTE-CONTAINER.

1,276,498.

Specification of Letters Patent. Patented Aug. 20, 1918.

Application filed October 4, 1917. Serial No. 194,735.

To all whom it may concern:

Be it known that I, JOHN W. CURRAN, a citizen of the United States, residing at Newport, in the county of Campbell and

5 State of Kentucky, have invented a new and useful Waste-Container, of which the following is a specification.

The invention relates to a waste holder, and more particularly to the class of waste 10 containers for journal boxes.

The primary object of the invention is the provision of a container of this character, wherein the waste or packing will be prevented from displacement, either longitudinally or laterally therein with the journal, thus minimizing the heating of the latter, and at the same time, retaining the lubricant in said box, which lubricant ordinarily becomes lost by dropping out from the rear 15 of the journal box, the container being designed to grip the bottom of the box, so as to hold it fixed, thereby avoiding the shifting of the waste or packing which ordinarily results in the same getting between 20 the bearings and journal, with the resultant heating of the latter and the wearing of said journal and bearings.

Another object of the invention is the provision of a container of this character, 30 wherein the construction thereof permits its use in various types of journal boxes, and also with those which have been in use, the construction of the container being novel in form to assure the proper circulation of a 35 lubricant, such as oil, and beneath the container is afforded a chamber for free oil, which by capillary attraction shall be drawn up through the waste, and thence on to the journal for its lubrication, after which such 40 oil will again gravitate beneath the container for further circulation.

A further object of the invention is the provision of a container of this character, which is extremely simple in construction, 45 thoroughly reliable and efficient, in its purpose, strong, durable and inexpensive in manufacture.

Other objects will be in part obvious and in part hereinafter pointed out.

50 The invention accordingly consists in the features of construction, combination of elements and arrangement of parts, which will

be exemplified in the construction herein-after set forth, and the scope of the application of which will be indicated in the following claims.

In the accompanying drawing:

Fig. 1, is a vertical central longitudinal sectional view through a journal box with the journal mounted therein, and showing 60 the improved waste container constructed in accordance with the invention within said box.

Fig. 2, is a sectional view on the line 2—2 of Fig. 1, looking in the direction of the 65 arrow, showing the container in top plan.

Fig. 3, is a vertical transverse sectional view through the journal box, journal and container.

Fig. 4, is a perspective view of the container looking toward its under side.

Referring to the drawing in detail, wherein like parts are designated by similar numerals of reference throughout the several views, A designates a portion of an integral 75 journal box casting of the ordinary well known construction and design, having in its rear end the usual transversely extending dust guard chamber 10, adapted to accommodate the dust guard, not shown, for 80 encircling the bearing 11, of the axle 12, formed with the journal 13, projecting into the rear end of the journal box A, and provided on its extremity with the usual axle collar 14. Within the journal box A, and 85 working against the journal 13 at its upper side between the bearing 11 and the collar 14, is the usual journal brass or bearing 15, held in place by the key 16, in the usual well known manner, while upon the bottom 90 of the journal box A, is the waste container, hereinafter fully described.

The waste container comprises a rectangular shaped plate 17, preferably made from sheet metal, and is dished or concave in cross 95 section to conform to the shape of the bottom of the journal box A, while marginally of this plate 17, is an outwardly and downwardly curved continuous flange 18, which rests upon the bottom of the journal box A 100 to elevate the plate 17, a distance from said bottom, for forming an oil chamber 19 therebetween, for a purpose presently described.

The plate 17, is cut centrally thereof lon-

gitudinally of the same to provide an elongated substantially rectangular shaped opening or slot 20, the side edges of which are formed with downturned blunt saw teeth 21, and the end edges with downturned lips or wings 22, which together with the teeth 21, are adapted to engage and grip the surface of the bottom of the journal box A, and the teeth 21, will hold the plate 17, fixed 10 within said journal box to prevent either longitudinal or lateral displacement thereof. The spaces or gaps between the teeth 21, at opposite side edges of the central opening or slot 20, provide notches 23, for 15 the free passage of oil into and from the chamber 19 afforded between the plate 17, and the bottom of the journal box.

The container is positioned in the journal box A, as shown in Figs. 1, 2, and 3 of the drawing, so as to occupy substantially the area of the bottom of the journal box, and upon this container constituted by the plate 17, is packed the waste or packing 24, which practically fills the journal box, and such waste or packing 24, sinks within the opening or slot 20, in said plate 17, to completely fill the same, so that the free oil within the chamber 19, will be drawn upwardly through the waste on to the journal box 20 when needed by capillary attraction. The sunken portion of the waste within the opening or slot 20, in said plate 17, will serve to anchor the waste to prevent any lateral or longitudinal displacement thereof with the journal 13, and thus avoid the shifting of the waste, which causes the journal to become heated, as said waste works upwardly between the bearings, and thus wipes the oil from the journal with resultant wearing out 25 of the journal and bearing. Furthermore, the sunken portion of the waste 24, in the opening or slot 20, prevents the waste from working to the front of the box, leaving the back part of the journal exposed, and as a result, lubrication ceases with the heating of the journal. The notches 23, between the teeth 21, will permit the free passage of the oil into the waste, and after said oil has circulated by being drawn upwardly on to the 30 journal through the waste, it will again drop therefrom by gravity into the chamber 19, between the plate 17, and the bottom of the journal box. By reason of the construction of the container, the circulation of the oil 35 is assured, without waste thereof by the dropping of the same through the rear end of the journal box. The dust guard chamber 10, has communication with the journal box by means of orifices 25, so that any oil 40 working into the chamber 10, will seep through the orifices 25, back into the chamber 19, in the container for the further circulation of said oil.

From the foregoing, it is thought that the

construction and manner of use of the container will be clearly understood, and, therefore, a more extended explanation has been omitted.

What is claimed is:—

1. A waste container of the character described comprising a plate, shaped correspondingly to the bottom of a journal box and having a marginal flange and also a central walled opening to provide an oil chamber between the wall of said opening and the marginal flange, the wall of said opening being notched at intervals for the ingress and egress of oil to and from the chamber. 70

2. The combination with a journal box 30 having waste therein, of a waste container comprising means interiorly of the box for engaging the bottom thereof to hold said container fixed, and also for anchoring the waste against displacement and constituting 35 an oil chamber.

3. The combination with a journal box having waste therein, of a waste container comprising means interiorly of the box for engaging the bottom thereof to hold said 90 container fixed, and also for anchoring the waste against displacement and constituting an oil chamber, said means being formed with a continuous marginal flange, and a central walled opening, a portion of the 95 waste being packed within the walled opening.

4. The combination with a journal box having waste therein, of a waste container comprising means interiorly of the box for 100 engaging the bottom thereof to hold said container fixed, and also for anchoring the waste against displacement and constituting an oil chamber, said means being formed with a continuous marginal flange and a 105 central walled opening, a portion of the waste being packed within the walled opening, the wall of the opening being formed with notches for the passage of oil within the chamber into and from the waste. 110

5. The combination with a journal box having a dust guard chamber and passages leading from the latter to the interior of the box, of a container comprising a plate dished in cross section and having a walled 115 central opening, waste confined within the journal box and a portion thereof sunk within the walled opening, the wall of the said opening being formed with blunt saw teeth for gripping engagement with the bottom 120 of the journal box and affording passages for the circulation of oil between the plate and the bottom of the box, and a marginal flange on said plate and resting upon the bottom of the box to form an oil chamber 125 about the walled opening.

6. A waste container for journal boxes comprising a plate shaped to fit the bottom

of the box, said plate having a central longitudinal opening and teeth provided at the walls of said opening and adapted to frictionally engage the bottom of the box and 5 hold the plate from movement.

In testimony, that I claim the foregoing

as my own, I have hereto affixed my signature in the presence of two witnesses.

JOHN W. CURRAN.
